UNITED STATES PATENT OFFICE.

WILLIAM X. STEVENS, OF WASHINGTON, DISTRICT OF COLUMBIA, ASSIGNOR TO ELLA L. BARTON, OF JACKSONVILLE, FLORIDA.

NAILING MECHANISM FOR BOX-MACHINES.

1,156,109.

Specification of Letters Patent. Patented Oct. 12, 1915.

Application filed September 12, 1911. Serial No. 648,913.

To all whom it may concern:

Be it known that I, WILLIAM X. STEVENS, a citizen of the United States, residing at Washington, in the District of Columbia, 5 have invented certain new and useful Improvements in Nailing Mechanism for Box-Machines, of which the following is a specification.

This invention relates to box making machines, particularly the parts which coöperate to do the nailing. Its object is to provide receptacles for holding nails in bulk, means for separating out the number of nails required for each box and means for 15 guiding these separate nails each to its right place for use, means for guiding each nail to enter straight into the box parts, and means for driving home at one movement the whole number of nails selected.

20 To this end my invention consists in mechanism for automatically nailing box ends hereinafter more fully described, reference being had to the accompanying drawings in which—

25 Figure 1 represents a nail hopper partly in side view, partly broken away and partly in transverse vertical section, Fig. 2 is a front end view on a smaller scale of the hopper partly broken away, Fig. 3 is a top 30 view of one nail delivery on a large scale, Fig. 4 shows a transverse section of one slide-way at line *x* Fig. 1, Fig. 5 shows a like section at line *y*. Fig. 6 is a side view of two nail chucks, and Fig. 7 shows a 35 transverse vertical section at line *z*, Fig. 6.

40 Numeral 8 represents a nail hopper, which comprises a box with sheet metal sides and a thicker bottom, 9, which inclines upward at 10, to carry the nails up to the top of the rails 11, and at the rear end the bottom is like a series of roofs, 12, inclined laterally to slide nails down into the grooves 13, between the rails 11. The hopper is journaled on a shaft 14, to be tipped backward and forward 45 every time a box is nailed. This is to tumble the bulk of nails to and fro and work them into the grooves 13, where they are caught by their heads on the side rails 11. A guard 15 is hung at 16 over each groove 13 to swing 50 down upon the rails at each backward tip of the box to keep in the groove all nails that have gathered there, and to swing upward as shown in Fig. 1 to let more nails pass forward. At the delivery end of the rails 11, a 55 picker box 17 having a shoulder 18, against

which the forward nail is stopped when a row of nails slide down the groove 13, is mounted in bearing 19 to slide to and fro across the ends of the rails. The forward movement may be actuated by a lever 20 60 which is suitably connected for operation by the machine, and the return movement is made by a spring 21. A picker 22, at each groove 13, is rigidly fixed to the picker bar 17, to pass at each forward movement, behind the body of the foremost nail, and when the delivery 23, through the bar 17, arrives over the throat 24 in the cross beam 25, the nail will have been wedged along the passage 26 into the delivery 23 when it will 65 be free to fall into the throat 24 and the pipe 27 to be conducted to the nail chuck 28. The lever 20 has a quick forward and back movement and the picker bar is immediately returned to its normal position, see Fig. 1, for 70 another nail to come against the shoulder 18. But now the whole hopper will be tipped backward and forward again to insure the gathering of nails in the slots and to knock 75 loose any bunches that may be wedged or 80 tangled. To insure the light nails coming forward to the picker I provide a pounder which comprises a weight 29, mounted for radial adjustment on an arm 30 that is journaled upon the shaft 14 to oscillate with the 85 hopper. When the hopper tips backward the lug 32 thereon carries the pounder until the hopper is at the end of its movement, when the pounder will be carried past its center of gravity over the shaft 14, and will 90 fall backward heavily upon the lug 31. When the hopper tips forward the lug 31 carries the pounder forward past center and then it falls against the lug 32. This 95 pounding helps to jar loose any nails that may be stuck in the passages and insures the foremost nails coming clear down against the bar 18 to be engaged by the pickers.

Each nail chuck comprises two jaws 28 100 hung in a fixed chuck guide 33, each jaw upon the upper edge of a bar 34. Each jaw is slotted to straddle its bar as shown in Fig. 7 and the lower end of the slot is wide to permit the jaws to swing back and 105 springs 35 press the jaws home upon the bars 34, as shown. At the upper end of the jaws the passage 36 between them is large enough to freely admit a nail head, then for about three quarters of the length of a nail the passage is barely large enough 110

to admit the body of the nail freely and for a short distance at the lower end the passage is nearly closed to prevent the nail dropping through. A plunger 37 for each 5 nail passage is carried by a vertically reciprocating hammer head, (not shown). A face plate 38 perforated at 39 to permit the passage of a nail and the plunger is rigidly secured upon the chuck guide 33 to prevent 10 roughness of the box lumber from interfering with the action of the jaws 28. A nail comes down the pipe 27 into the passage 36, the plunger comes down and drives the nail, causing it first to wedge the jaws apart at 15 their lower ends, so that when the nail starts to enter the box, which is close up to the plate 38, the nail will be guided both by its head and point to enter straight, and when the head comes into the narrow passage be- 20 tween the jaws 28, they are wedged outward. It would be practically impossible to drill a small hole through the whole length of the chuck guide 33, corresponding to the width of the box to be nailed, to 25 admit a pin on which chuck jaws could be hung at the point corresponding to the upper edge of the bar 34. Therefore this bar is substituted as a hanger for the jaws and is rigidly secured to the guide 33 by 30 pins 40. By swinging the guards 15 over backward they will prevent nails from going forward to the pickers if by any oversight the machine is started up when boxes are not to be nailed.

35 Having thus fully described my said invention, what I claim as new and desire to secure by Letters Patent, is:

1. In mechanism for automatically nailing boxes, a hopper hung to be tipped back-

ward and forward and having rails in pairs 40 to receive nail bodies between them, and standing above the level of the bottom, the bottom having inclined portions rising rearward higher than the said rails and slanting roof-shaped transversely to the tops of the 45 rails, and guards pivoted above each pair of rails in front of the elevated rear portions thereof and arranged to rest upon the tops thereof and hold the nails collected in the slots in front thereof during the upward 50 tilting of the front of the hopper, substantially as set forth.

2. A nail feeding mechanism comprising an oscillatory hopper having a bottom formed with a series of parallel slots and 55 inclined portions rising rearwardly and above said slots and slanting roof-shaped transversely to said slots, and a reversible guard pivoted above each slot in front of the elevated rear portions and adapted to 60 hold the nails collected in said slots in front thereof during the oscillation of said hopper when in use, any one or more of said 65 guards adapted to be oscillated at any time into such a position as to prevent the passage of nails along their respective slots during the oscillation of said hopper when such slots are not in use, substantially as set forth.

In witness whereof, I have hereunto set 70 my hand and seal at Washington D. C. this 26th day of August, A. D. nineteen hundred and eleven.

WILLIAM X. STEVENS. [L. S.]
